ABSTRACT

The method and apparatus is disclosed for driving a plasma display panel to invert the state of a discharge cell included in the panel. The state of a selected cell is changed by a preparatory inverting pulse which is applied to a selected column (or row) electrode, and then an inverting pulse is applied to a selected row (or column) electrode to invert the state of the changed cell wall voltage. Thus, semi-selection trouble does not take place according to this invention.

METHOD FOR DRIVING A PLASMA DISPLAY PANEL

BACKGROUND OF THE INVENTION

1. Field of the Invention

This invention relates to the apparatus and method for driving a plasma display panel, and in particular, to the apparatus and method of inverting the state of a discharge cell, that is, inverting the state from "write" to "erase" and vice versa.

2. Description of the Prior Art

A typical plasma display panel of the prior art is composed of a pair of electrodes coated by a dielectric layer such as glass. The electrodes are opposed to each other, and the space therebetween is filled with a suitable discharging gas such as neon. Letters or figures are displayed by a discharge spot in the discharge cell formed between the opposed electrodes, and memory function is carried out by wall charges accumulated in the dielectric layer. A wall voltage generated by the wall charges depends on a sustaining voltage and if the waveform of the applied sustaining voltage is, for instance, symmetric, the wall voltage takes a value between zero and a level, that is, between the erase state and the write state. When a non-symmetric sustaining voltage is applied, the wall voltage can assume either of two stable states, positive and negative (it may be said to take three stable states if the zero level is taken into account).

In the case of applying a symmetric voltage, a pulse-like sustaining voltage V_s is previously applied so that the voltage in the discharging space periodically changes its polarity as shown in FIG. 1. If a writing voltage V_w higher than the firing voltage V_f is applied, a discharge spot is produced in the discharge cell, the wall charges are accumulated in the dielectric layer and the wall voltage V_Q is established as shown by the dotted line. Thus, the potential difference between the next sustaining voltage V_s and the wall voltage V_Q approaches a value more than the firing voltage V_f , and hence a discharge spot is produced again so that the polarity of the wall voltage V_Q is inverted. Therefore, if once a writing is done and if the applied sustaining voltage V_s established at a level lower than the firing voltage V_f remains, a discharge spot is produced every time the polarity of the sustaining voltage V_s is inverted, and thus the written information is stored and displayed. In order to invert the above-mentioned state, that is, to erase, an erasing voltage V_E is applied, whose pulse width is narrow or whose peak value can barely cause a discharge. By this erasing voltage V_E , a discharge spot is instantaneously produced in the discharge cell but the wall voltage is not produced by the next sustaining voltage so that the display is erased.

The potential difference between such erasing voltage V_E and the wall voltage due to the previous sustaining voltage has to exceed the firing voltage V_f . The wall voltage after inversion depends on the pulse width. If the pulse width is narrow, the voltage can be rather high and the voltage just after the application of the sustaining voltage is different from the voltage remaining after a lapse of time, the level of which depends on the cell to some extent. Therefore, the range of the height and width of the pulse of the erasing voltage is very small and hence the inversion from display to erase modes of operation cannot be surely carried out.

The selection of the discharge cell to be energized by inverting its wall voltage, is done by so-called voltage coincidence method wherein driving is done from both electrodes and the desired inverting pulse is applied only to the electrodes of a single cell when the driving voltages come to equal value, and hence the discharge is occasionally made by a pulse voltage applied to a single electrode (so-called semi-select trouble).

In the case of applying a non-symmetric sustaining voltage, the sustaining voltage is composed of waveforms A and B as shown in FIG. 2. The waveform A includes a pulse a_1 of a voltage $+V_H$ and a pulse a_2 of a voltage $-V_L$, and the waveform B includes a pulse b_1 of a voltage $-V_H$ and a pulse b_2 of a voltage $+V_L$. When the wall voltage is V_{Q1} , a discharge spot SP1 is produced by only the voltage of the waveform A, and when the wall voltage is V_{Q2} , a discharge spot SP2 is produced by only the voltage of the waveform B. If the ratio of the number of the waveforms A to that of the waveform B is 1:10, the ratio of the brightness of the state 1 of the wall voltage V_{Q1} to that of the state 2 of the wall voltage V_{Q2} is about 1:10, and hence a display can be carried out by the state 2. Therefore, a memory function is provided with the state 1 corresponding to a logic "0" and the state 2 to a logic "1," for instance.

When the conversion of the states is done, converting pulses CP1, CP2 and CP3 of the voltage V_a are applied as shown in FIGS. 3A, B and C. FIG. 3A shows the case of conversion from the state 1 to the state 2, wherein the wall voltage V_{Q1} is converted to the wall voltage V_{Q2} by the converting pulse CP1 as shown by the arrow. FIGS. 3B and 3C show the case of conversion from the state 2 to the state 1, wherein the wall voltage V_{Q2} is converted to the wall voltage V_{Q1} by the converting pulses CP2 and CP3 as shown by the arrow. The purpose of the pulses CP1, CP2 and CP3 is the same as the converting pulse V_w shown in FIG. 1, and these pulses are applied to the selected cell according to the voltage coincidence method. Accordingly, the possibility of semi-select trouble is high.

BRIEF SUMMARY OF THE INVENTION

An object of this invention is to provide a sure transition of the state of the discharge cell without semi-select trouble.

Another object of this invention is to enlarge the extent of the transition of the state of the discharge cell.

In order to accomplish these and other objects, according to this invention, the transition of the state is carried out in two steps. The first step, a preparatory converting voltage is applied to the row (or column) electrode of the selected discharge cell to change the polarity of the wall voltage, and second, a converting voltage is applied to the column (or row) electrode to change the state of the selected discharge cell. The potential difference between the converting voltage and the wall voltage changed by the preparatory voltage exceeds the firing voltage.

BRIEF DESCRIPTION OF THE DRAWINGS

This invention will be more fully described in conjunction with the drawings, which include:

FIG. 1 is a graph of the prior art showing the conversion of the voltage states of a discharge cell upon applying a symmetric sustaining voltage;

FIG. 2 is an explanatory graph of the function upon applying a non-symmetric sustaining voltage;

FIGS. 3A, B and C are graphs showing the voltage states of a discharge cell of the prior art and, in particular, showing the conversion of the state of a discharge cell upon applying a non-symmetric sustaining voltage;

FIG. 4 is an explanatory view of the electrodes and discharge cells of a plasma display panel;

FIGS. 5A to E show a series of graphs explaining the conversion of the state of a discharge cell according to the teachings of this invention upon applying a symmetric sustaining voltage;

FIG. 6 is a block diagram of a circuitry in accordance with this invention for carrying out the function shown in FIG. 5;

FIG. 7 shows the waveforms for explaining the function of the parts of the circuitry shown in FIG. 6;

FIGS. 8A to E show a series of graphs as another example of the conversion of the state of a discharge cell according to this invention upon applying a non-symmetric sustaining voltage;

FIG. 9 is a block diagram of a circuitry for carrying out the function shown in FIG. 8;

FIG. 10 shows an example of the gate circuit shown in FIG. 9;

FIG. 11 shows an example of the driver shown in FIG. 9;

FIG. 12 shows an example of the decoder shown in FIG. 9;

FIGS. 13A to S show the waveforms for explaining the functions of the parts of the circuitry shown in FIG. 9; and

FIGS. 14A to H show the waveforms of various non-symmetric sustaining voltages.

DETAILED DESCRIPTION OF THE INVENTION

FIG. 4 shows schematically a plasma display panel wherein the electrodes X_a and Y_a are selected to convert the state of a discharge cell A.

In the case of applying a symmetric sustaining voltage, a voltage V_{xa} shown in FIG. 5 is applied to the selected electrode X_a while a voltage V_{ya} is applied to the selected electrode Y_a , and hence a voltage V_A is applied to the selected discharge cell A. That is, a preparatory converting voltage V_p is applied after the application of the sustaining voltage V_s to convert the wall voltage V_q . Next, a converting voltage V_d is applied so that the potential difference between V_d and V_q exceeds the firing voltage V_f ; immediately, the discharge is started, but the wall voltage V_q is distinguished because the pulse width of V_d is too small to produce the wall voltage. A voltage V_B is applied to a semi-selected cell B on the electrode Y_a . The time when the discharge spot is generated, shifts to the time when the preparatory converting voltage V_p is applied, the converting voltage V_d is not applied, and hence the conversion of the state does not take place. A voltage V_c is applied to the semi-selected discharge cell C on the electrode X_a , and the conversion of the state does not occur in like manner because the converting voltage V_d has the same polarity as the previous sustaining voltage V_s . Therefore, semi-select trouble does not appear.

A device for carrying out the above-mentioned driving method is shown in FIG. 6, and its function will be hereinafter explained on referring to FIG. 7. A sustaining voltage V_s , a preparatory converting voltage V_p , and a converting voltage V_d are applied to a plasma display panel 1 by drivers 2 and 3 composed of a group of amplifiers such as transistors or the like. These drivers 2 and 3 are controlled by the output of gate circuits 4 and 5 composed of a plurality of AND gates and OR circuits. The logical functions of the gate circuits 3 and 4 are carried out under the control pulse of a location pulse generator 10 and the output of address registers 6 and 7. The address signals are applied to convert the state of the selected cell through input terminals 8 and 9.

10 The location pulse generator 10 includes a counter 12 which counts the clock CL derived from a clock generator 11, the counter 12 being shown as an octal notation counter in FIG. 6. The output signals of the counter 12 are denoted as (1) to (8); the output (1) is 15 coupled to the gate circuit 4 and the sustaining voltage V_s is applied to each row electrode from the driver 2. The output (6) is applied to the gate circuit 5 and the sustaining voltage is applied to each column electrode from the driver 3.

20 Address signals are added to the input terminals 8 and 9, and the state converting signal, which is an erase-command signal in this example, is applied to the input terminal 13 to enable an AND gate 14 and to reset a flip-flop 15 by the output (2) of the counter 12.

25 The flip-flop 15 is set by the output (5) and hence the $\bar{Q}$ output of the flip-flop 15 takes a form shown as (15) in FIG. 7. The output (15) of the flip-flop 15 is coupled to the AND gates 16 and 18 and an output signal (16) of the AND gate 16 is derived from the output signal (3) of the counter 12 to be applied to the gate circuit 5. The preparatory converting voltage V_p is applied to only selected column electrodes from the AND gate 16 and the output of address register 7. The output of the counter 12 is added to a waveform shaping-and-delay 30 circuit 17. This circuit 17 is composed of, for instance, a monostable multi-vibrator and a delay-line, and its input pulse is waveform-shaped to a narrow pulse by the monostable multi-vibrator. Thus, the output signal (18), as shown in FIG. 7, of the AND gate 18 is a pulse output having a width smaller than the output signal (4) of the counter 12, and it is delayed from the leading edge of the output signal (4). The output signal (18) is added to a gate circuit 4 and the output of the address register 6 is also added to the gate circuit 4 and hence 35 the converting voltage V_d is applied to only selected row electrodes by the driver 2. Thus, one voltage denoted as V_{xa} is applied to selected row electrodes and another voltage denoted as V_{ya} to selected column electrodes to effect a state conversion or erasure in the selected cell without semi-select trouble, as shown on reference to FIG. 5. The peak value of the preparatory converting voltage V_p and the converting voltage V_d may be equal to that of the sustaining voltage V_s , and hence the circuit of the drivers 2 and 3 is simple. After the state conversion, the output signal (18) of the AND gate 18 is delayed through the delay circuit 19 and added to the address registers 6 and 7 so that these registers are reset.

40 In contrast to the above example, the preparatory converting voltage V_p may be applied to the selected row electrodes and the converting voltage to the selected column electrodes. In an alternative method of applying the sustaining voltage, one half of it may be applied to the row electrodes while another half is applied simultaneously to the column electrodes in the opposite polarity. In a still further embodiment, a sustaining voltage, which changes periodically its own po- 45 50 55 60 65

larity, may be applied to either one of the row or column electrodes. In short, the preparatory converting voltage V_p is applied to either the row or column electrodes, the wall voltage of the discharge cell on the selected electrodes is changed, and then the converting voltage V_d is applied to the other selected electrodes so that the state of the selected cell is converted.

The examples described above relate to the case of applying a symmetric sustaining voltage; the case of a non-symmetric sustaining voltage will be explained as follows. When a voltage V_{xa} composed of voltages V_1 and V_d is applied to a selected electrode X_a and a voltage V_{ya} composed of V_2 and V_p is applied to another selected electrode Y_a , a resultant voltage V_A is applied to a selected cell A as shown in FIG. 8C. Accordingly, the wall voltage V_{q1} is changed by the preparatory converting voltage V_p . Then discharge occurs once by the converting voltage V_d when the potential difference between the changed wall voltage and the converting voltage V_d exceeds the firing voltage V_f . However, the wall voltage reaches the level V_{q2} because the pulse is not sufficiently wide. A voltage V_B is applied to the semi-selected cell B on the selected electrode Y_a and a discharge spot is produced by the preparatory converting voltage V_d but the state is not changed. A voltage V_d is applied to the semi-selected cell C on the selected electrode X_a and the state is not changed because the voltage V_c has the same polarity as the sustaining voltage V_1 . Thus, the state of the selected cell can be converted without semi-select trouble.

Referring to FIG. 9, a circuit for driving the display panel will be described as follows. In a plasma display panel 31, the sustaining voltage is applied to each electrode from drivers 33 and 35 which are controlled by the outputs of the gate circuits 37 and 39. The outputs of a location pulse generator 40 and decoders 42 and 44 are applied to the gate circuits 37 and 39, respectively. Input address data signals XD and YD are applied to the decoders 42 and 44 from address registers 46 and 48 to be decoded.

The location pulse generator 40 includes a clock generator 51, a counter 50, a J-K flip-flop 54, AND gates 56, 57, and 58, OR circuits 62 and 64, a monostable multivibrator 66, and a conversion-demand signal CNG is added to AND gate 58. The counter 50 is an undecimal counter in this example, and its output signals are denoted as (1) to (11). Output signals (1) and (10) are coupled to the gate circuit 37 through the OR circuit 64, and the output (1) is connected to the driver 33. Output signals (6) and (8) are connected to the gate circuit 39 through the OR circuit 62 and the output signal (8) is coupled to the driver 35.

Gate circuits 37 and 39 each comprises illustratively, as shown in FIG. 10, an AND gate 60 and an OR circuit 62. In the gate circuit 37, the outputs of the decoder 42 and the monostable multivibrator 66 come to the input of the AND gate 60; the outputs of the AND gate 64 and the AND gate 60 are coupled to the inputs of the OR circuit 62, and the output of the OR circuit 62 is connected to the driver 33. In the gate circuit 39, the output signals of the decoder 44 and the AND gate 50 are connected to the input of the AND gate 60; the output signals of the OR circuit 62 and the AND gate 60 are both connected to the inputs of the OR circuit 62, and the output of the OR circuit 62 is added to the driver 35.

An example of the driver 33 (or 35) is shown in FIG. 11, wherein Q1 to Q12 are transistors and D1 is a diode. The output signal of a monostable multivibrator 66 is applied to the base of the transistor Q2 and it controls the switching of the transistor Q1. The output signal (1), as shown in FIG. 13B, of a counter 50 is coupled to the base of the transistor Q4 to control the switching of the transistor Q3. The output signals of the gate circuit 37 are coupled to the bases of the transistors Q6, Q8, Q10 and Q12, respectively, to control the switching of the transistors Q5, Q7, Q9 and Q11 and to generate the voltages V_H , V_L and V_d at the electrodes X_1 to X_n . The driver 33 is generally the same as the driver 35, but does not include transistors Q1 and Q2.

An example of decoders 42 (or 44) is shown in FIG. 12. Any one of the output signals of the NAND gates 70 to 79 comes to zero by the input of 1248 codes. Numerals 80 to 83 also denote NAND gates.

Next, referring to FIGS. 13A to S, the function of the circuit of FIG. 9 will be explained. The clock CL (FIG. 13A) of the clock generator 51 is counted by the counter 50, and the signals (1), (3), (5), (6), (8) and (10) are shown in FIGS. 13B, C, D, E, F and G, respectively. The output of the OR circuit 64 is shown in FIG. 13H. Output signal VMMV is derived from the output of the monostable multivibrator 66, and is shown in FIG. 13M. The signal VFF is shown in FIG. 13N as the output of the flip-flop FF, signals V_x and V_y are the voltages applied (see FIGS. 13Q and R) to the row and column electrodes, and signal VA is shown in FIG. 13S as the voltage applied to the selected cell. Usually, the preparatory converting voltage and the converting voltage, the hatched parts of the voltages V_x and V_y , are not applied. The voltage V_L is applied through the diode D1 shown in FIG. 11, simultaneously with the output (10) of the counter 50 to the row electrode and with output (6) of the counter 50 to the column electrode. The voltage V_H is applied through the transistor Q3, simultaneously with the output (1) of the counter 50 to the row electrode and with the output (8) of the counter 50 to the column electrode.

When the conversion-command signal CNG is applied to the AND gate 58, the output signal of the AND gate 58 is applied to the flip-flop 54 simultaneously with the output signal (1) of the counter 50, and the flip-flop 54 is set by the next clock CL and reset by the output (6). When the flip-flop 54 is set, the AND gates 56 and 57 are enabled by the output of the flip-flop 54 and the output (3) of the counter 50 is coupled to the gate circuit 39. At this time, the input address data YD is decoded by the decoder 44 and applied to the gate circuit 39, and hence the preparatory converting voltage V_p of the voltage V_L is applied only to the selected column electrode. The output (5) of the counter 50 is connected to the monostable multivibrator 66 from the AND gate 57, converted to a narrow pulse and applied to the gate circuit 37 and the driver 33. This pulse is applied to the base of the transistor Q2 shown in FIG. 11 and the transistor Q1 is converted "on," whereby the transistor Q1 is converted to the on-state and the converting voltage V_d is applied.

At the same time, the input address data XD is decoded by the decoder 42 and coupled to the gate circuit 37, and hence the converting voltage is applied only to the selected row electrode. Thus, the voltage VA is applied to the selected cell A. The wall voltage V_{q1} is changed by the preparatory converting voltage

V_p and the potential difference between the converting voltage V_d and the changed wall voltage exceeds the firing voltage V_f , so that the discharge takes place. However, the pulse width of voltage V_p is not wide enough to establish the wall voltage and hence the wall voltage is converted to the level V_{q2} . Converting the semi-selected cell, the semi-select trouble does not take place as described in reference to the graphs of FIG. 8.

The above example is the case when the state 1 of the wall voltage V_{q1} is converted to the state 2 of the wall voltage V_{q2} , and the conversion from the state 2 to the state 1 can be done in a similar way. The method shown in FIG. 3C can be combined with the method mentioned just above. The preparatory converting voltage V_p and the converting voltage V_d may be added to either column or row electrode as well as in the case of the above-mentioned symmetric sustaining voltage.

FIGS. 14A to H show the various methods of applying the sustaining voltage. In FIGS. 14A and B, two types of voltages, i.e., half of V_H and half of V_L , are applied to the column and row electrodes at the same time and in the opposite polarities. The nonsymmetric sustaining voltage combine with V_H and V_L and are applied to the discharge cell. The preparatory converting voltage and the converting voltage are applied in the same way as in the above-described example. FIGS. 14C and D show a case wherein the voltages V_H and V_L are applied to the row and column electrodes, respectively. FIGS. 14E and F show a case wherein a voltage corresponding to V_L has a narrow width and a peak value generally equal to V_H . FIGS. 14G and H show the sustaining voltage in the case wherein the state of the wall voltage has three stable states, that is, high, low and zero; further, the waveform of the preparatory converting voltage is able to be the same as that of the sustaining voltage.

As described above, according to this invention, conversion of the state is carried out in two steps, wherein the preparatory converting voltage and the converting voltage are successively applied, and in the semi-selected cell to which the preparatory converting voltage is applied; the time when the wall voltage is changed, is shifted but the state is not converted. In the semi-selected cell to which the converting voltage is applied, the potential difference between the converting voltage and the previously applied sustaining voltage is less than the firing voltage V_f , and hence the discharge does not take place and the state is not converted. Accordingly, the semi-select trouble does not appear at all and the range of the converting voltage, that is, the range of the peak value and pulse width, can be extended. The preparatory converting voltage may have the same waveform as the sustaining voltage and the circuit need not be complicated.

Numerous changes may be made in the above described apparatus and the different embodiments of the invention may be made without departing from the spirit thereof; therefore, it is intended that all matter contained in the foregoing description and in the accompanying drawings shall be interpreted as illustrative and not in a limiting sense.

What we claim is:

1. Apparatus for selectively displaying and storing information, said apparatus comprising:

a plasma display panel comprising a plurality of energizable radiation emitted elements disposed in an array, each of said emitting elements having first

and second electrodes defining a discharge region therebetween for receiving a discharge gas and wall covering for storing wall charges, said emitting elements having a characteristic firing voltage;

first means for applying a preparatory converting voltage to the first electrode of a selected emitting element of sufficient magnitude to convert the voltage of the wall charges of the selected emitting cell to a changed voltage; and

second means for applying a converting voltage to the second electrode of the selected emitting cell of a selected pulse width sufficient to convert the state of the selected emitting cell from its display-state to its erase-state, the potential difference between the converting voltage and the changed voltage of the wall charges of the emitting cell being not less than the firing voltage of the selected emitting element.

2. Apparatus as claimed in claim 1, wherein there is further included means for applying a sustaining voltage to each emitting element, and wherein said first means provides the preparatory converting voltage of a waveform substantially similar to that of the sustaining voltage.

3. Apparatus as claimed in claim 2, wherein said first means provides the converting voltage of a peak value substantially equal to that of the sustaining voltage and the pulse width of the converting voltage is not greater than the pulse width of the symmetric sustaining voltage.

4. A method of selectively energizing a plasma display panel comprising a plurality of pairs of spaced electrodes for defining a discharge space therebetween filled with a discharge gas, each of the electrode pairs having a dielectric layer for forming thereon a wall voltage maintained by periodic sustaining voltage signals applied to the electrodes to effect a discharge between the electrodes of a pair, whereby the wall voltage is changed from a first state to a second state, said method comprising the steps of:

applying a first voltage signal to the one electrode of a selected electrode pair during one cycle of said sustaining voltage signals, said first voltage signal having a potential difference with respect to the sustaining voltage signals and a pulse width of sufficient magnitudes to produce a discharge to convert the wall voltage; and

thereafter applying a second voltage signal of opposite polarity to said first voltage signal to the other electrode of said selected electrode pair during said one cycle of the sustaining voltage signal, said second voltage pulse having a potential difference with respect to the converted wall voltage produced by said first voltage signal, and a pulse width of sufficient magnitudes to produce a discharge to convert the wall voltage to its second state.

5. The method as claimed in claim 4, wherein the sustaining voltage signal is symmetric, said first voltage signal is substantially similar in waveform to that of the symmetric sustaining voltage signals, said second voltage pulse having a peak value approximately equal to that of the sustaining voltage signals and a pulse width smaller than that of the symmetric sustaining voltage signal.

6. The method as claimed in claim 4, wherein the sustaining voltage signals are non-symmetric and have high and low peak values, said first voltage signal is sub-

stantially similar in waveform with respect to that of the non-symmetric sustaining voltage signals of low peak value, and said second voltage signal having a peak value intermediate between the high and low peak values of the non-symmetric sustaining voltage signals and a pulse width smaller than that of the non-symmetric sustaining voltage signals of high peak value.

7. Apparatus for selectively displaying and storing information comprising:

a plasma display panel including a plurality of pairs of spaced electrodes each defining therebetween a discharge space filled with a discharge gas and coated with a dielectric layer for forming thereon a wall voltage disposable in first and second states; first means for applying a periodic sustaining voltage signal to said electrode pairs to effect a discharge between said electrodes whereby the wall voltage is disposed from its first to its second state; second means for applying a first voltage signal to one electrode of a selected electrode pairs during one cycle of said sustaining voltage signal, said first voltage signal having a potential difference with respect to said sustaining voltage signal and a pulse width of sufficient magnitudes to produce a discharge to convert the wall voltage; and third means for applying a second voltage signal of opposite polarity to said first voltage signal to the

other electrode of said selected electrode pair during said one cycle of the sustaining voltage signal, said second voltage signal having a potential difference with respect to that wall voltage produced by said first voltage signal and a pulse width of sufficient magnitudes to effect a discharge to convert the wall voltage to its second state.

8. Apparatus as claimed in claim 7, wherein said first means provides a symmetric sustaining voltage signal, said first voltage signal being substantially similar in waveform to that of said symmetric sustaining voltage signal, and said second voltage signal has a peak value approximately equal to that of said symmetric sustaining voltage signal and a pulse width smaller than that of said symmetric sustaining voltage signal.

9. Apparatus as claimed in claim 7, wherein said first means provides non-symmetric sustaining voltage signals of high and low peak values, said first voltage signal being substantially similar in waveform to that of said non-symmetric sustaining voltage of low peak value, and said second voltage signal having a peak value intermediate of said high and low peak values of said non-symmetric sustaining voltage signals and a pulse width smaller than that of said non-symmetric voltage signal of a high peak value.
